UNITED STATES PATENT OFFICE

106,435

DESIGN FOR A GLIDER OR SIMILAR ARTICLE

Samuel M. Fischer, Pittsburgh, Pa., assignor to
John Fischer, Pittsburgh, Pa., trading as
Fischer Bed Spring Company

Application July 1, 1937, Serial No. 70,205

Term of patent 3½ years

To all whom it may concern:

Be it known that I, Samuel M. Fischer, a citizen of the United States, residing at Pittsburgh, in the county of Allegheny and State of Pennsylvania, have invented a new, original, and ornamental Design for a Glider or Similar Article, of which the following is a specification, reference being had to the accompanying drawing, forming part thereof.

In the drawing:

Fig. 1 is a perspective view of a glider or similar article, showing my new design;

Fig. 2 is an end elevational view thereof; and
Fig. 3 is a front elevational view of an end portion of Fig. 1, with the cushions removed.

I claim:

The ornamental design for a glider or similar article, as shown.

SAMUEL M. FISCHER.
